UNITED STATES PATENT OFFICE.

JAMES E. DAVENPORT, OF NEW YORK, N. Y., ASSIGNOR TO UNION TECHNICAL CORPORATION, OF NEW YORK, N. Y., A CORPORATION OF NEW YORK.

ROTARY ENGINE-VALVE.

1,305,695.

Specification of Letters Patent.

Patented June 3, 1919.

Application filed October 25, 1917. Serial No. 198,539.

To all whom it may concern:

Be it known that I, JAMES E. DAVENPORT, a citizen of the United States, and resident of 125 West 119th street, New York city, in 5 the county of New York and State of New York, have invented certain new and useful Improvements in Rotary Engine-Valves, of which the following is a specification.

My invention relates to engines and has 10 for its object a rotary valve to admit and exhaust gases from cylinders, and is useful with one or more cylinders.

The object of my invention is a valve provided with suitable packing to render the 15 passage from the valve into the cylinder gas-tight and to prevent leakage from the inlet valve opening to the exhaust valve opening and vice versa.

It consists further of means which 20 through use and its consequent wear become more perfect in operation.

A further object of my invention is a valve head capable of being applied to standard forms of engines, so that the valve 25 and other operating members may be removed therefrom.

In the drawings:

Figure 1 is a section upon the line 1—1 30 Fig. 2 showing a cross section of my valve in its head.

Fig. 2 is a longitudinal section thereof upon the line 2—2 Fig. 1.

Fig. 3 is a longitudinal view partly in section of my invention as applied to a plurality of cylinders and part of the mechanism, duplicates of parts shown being omitted.

Fig. 4 is a view, partly in section, of the valve proper.

Fig. 5 shows the gear which rotates it.

Fig. 6 shows how the power is taken off from the shaft of the engine to drive the gear, Fig. 6 being shown in reduced size.

Fig. 7 is a section of Fig. 3 upon the line 7—7.

Fig. 8 is the left hand end of the parts shown cut off in Fig. 5.

My invention consists in a pipe 1 having a conduit 2 adapted to deliver the mixture 50 to the cylinders, a series of ports 3, one for each cylinder adapted to register during the rotation of the valve with the inlet passageways 4 leading into the cylinder spaces 5. The valve is provided also with a concentric

space 6 surrounding the inlet pipe and 55 adapted to conduct exhaust gases away from the cylinders, ports 7, one over each cylinder, in the pipe 7^a being adapted to register with the passageways 4 for the purpose of receiving the exhaust gases. Surrounding 60 the valve is a shoe 8 cut open at 9 and provided with a cylindrical floating projection 10 having packing rings 11, like those of a piston, engaging the wall of the chamber 12 in the casing 13 of the valve head. This 65 casing may be provided with a water chamber 14 connecting with the water chamber 15 in the upper half of the valve head 16 adapted to be bolted to the lower portion of the valve head by means of bolts 17. 70

Surrounding the shoe 8 and located within the valve casing is an additional shoe 18 extending from the point 19 to the point 20 and held in place against rotation by fixed abutments 21 and 22 which may form an 75 integral portion of the valve casing at 13 and if desired be machined separately and secured thereto by any suitable means.

Each shoe 8 and 18 is adapted to hug the part within it and maintain a tight joint 80 therewith. The shoe 18 is preferably provided with flanges 19 adapted to come into contact with the top of the outside 20' of the valve member 7^a to prevent escape of gases laterally from the spaces between the 85 split open ends 9 of the shoe 8.

It will be evident from this construction that the shoe 8 will cling to the valve and make a tight joint therewith as the valve rotates and that the cylindrical projection 10 90 prevents it from being rotated with the valve, while the packing rings 11 maintain a tight joint so that gases from the port 4 are unable to escape from the ends of the packing shoe 8. The projection 10 fits 95 fairly snugly, allowing for variations in exhaustion, over the cylindrical member 23, which forms a passageway for the gases from the port 3 to the cylinder space 5. The member 23 and the shoe 8 are cut out 100 at 24 to provide a downward pressure against the bottom of that member and thus establish a balance of gas pressure thereon, so that the position of the member 10 will be entirely established by the position of 105 the rotation of the valve member 7^a.

This is my preferred form of construction.

In Fig. 3, it is shown how this valve is mounted at one end upon a suitable bearing 25 located in the casing and upon another bearing 26 also located in the casing. Other intermediate bearings may be employed if desired. This valve, at its left hand, ends in the shaft 27 adapted to be driven by a worm gear 28 and worm 29. Some of the parts described in Figs. 1 and 2 are shown in this figure. Between the lines 30 and 31 5 may be located as many pairs of inlet and exhaust ports as there may be cylinders. The right end of the outer member 7^a of the valve is mounted in the bearing 26 and 10 delivers to the hollow member 32 which is secured by suitable means to the casing at 32^a. The inner tube of the valve is adapted 15 to receive mixture through the hollow member 33 which may be secured to the member 32^a and provided with packing 34 to maintain a tight joint between the inlet and exhaust passageways.

In Fig. 4 are shown the various ports 3 positioned at 90° from each other around the 25 axis of the valve. The exhaust ports 7 are likewise shown positioned at 90° from each other around the axis of the valve. The valve is geared preferably to rotate once while the crank shaft rotates twice. This 30 operation is suitable for the four-cycle gas engine. When used for two-cycle purposes, either for gas engines or steam engines, the valve should rotate at the same speed as the crank shaft.

35 The exhaust gases may be discharged through the connection 32 and passageway 35. The valve and its various shoes may be properly secured in place when the upper half 16 of the casing is bolted to the lower 40 part 13 of the casing by the bolts 17. The bearings also may be located and housed in place at the same time. After these two parts of the casing have been bolted together, the attachments 32 and 33 may be bolted 45 to the casing at one end and the disk 36 at the other end may be screwed into place. An oil supply pipe 37 may deliver oil wherever desired, and other suitable oil connections well known may be employed. Both 50 parts of the casing may be suitably provided with water chambers interconnecting with each other as indicated by the broken lines 38, and one or more water supply pipes 39 may be located wherever desired to supply 55 and withdraw water from the casing and also from the cylinders, when so desired, for the purpose of cooling the engine.

In Fig. 5, the worm 29 is shown mounted in bearings 40 in the member 41 which is 60 journaled freely upon the shaft 27. The worm gear 28 is adapted to be keyed to the shaft by means of the key way 42. The member 41 is held in place by the bolt 43 shown in Fig. 3. The abutment 44 may be 65 employed to prevent the worm rising and

the abutment 45 (see Fig. 6) may prevent the shaft carrying the worm 29 from being pushed downward. The worm 29 may be keyed to shaft 46, at the lower end of which (see Fig. 6) may be another worm 47 adapted 70 to be driven by the worm gear 48, the shaft 46 being journaled at 49 in the member 50 and the member 50 being journaled upon the end 51 of the crank shaft of the engine. The gear 48 may be keyed to the shaft 51. 75 The pitches of the various worms and gears may be varied to suit the type of engine. In a four-cycle engine, the worm gear should be so proportioned as to drive the valve one complete rotation to two rotations of the 80 crank shaft 51. In a two-cycle engine, either gas or steam, the valve 1 should be driven at the same speed as the crank shaft.

The casing 52 may be the ordinary engine casing and may have mounted thereon the 85 cylinder 53 (see Fig. 1), the said casing and cylinder adapted to hold the usual piston, piston rod and crank shaft and such other parts as may coöperate with their operation. This particular valve head is adapted to fit 90 an engine of the type known as the "Overland". It may be altered to suit any other standard type of engine, when so desired.

Many variations may be made within the scope of my invention, its principal features 95 being pointed out in the accompanying claims.

What I claim is:—

1. In an engine containing a driving mechanism, a rotary valve adapted to be 100 rotated by said mechanism, alternately presenting inlet and exhaust ports to coöperate with said mechanism, a shoe embracing said rotary valve substantially more than 180° and thus provided with means to cause it 105 to cling to said valve, said shoe provided with portions surrounding the passageway adapted to register with the ports of said valve, said shoe having a circular projection provided with means to form a gas-tight 110 joint with a casing connected to said mechanism.

2. The combination in claim 1 having said circular projection cylindrical in form.

3. In an engine containing a driving 115 mechanism, a rotary valve adapted to be rotated by said mechanism, alternately presenting inlet and exhaust ports to coöperate with said mechanism, a shoe embracing said rotary valve substantially more than 180° 120 and thus provided with means to cause it to cling to said valve, said shoe provided with portions surrounding the passageway adapted to register with the ports of said valve, said shoe having a circular projection provided with means to form a gas tight joint with a casing connected with said mechanism, said shoe surrounding said valve being split to form resilient arms to enable it 125 to cling to said valve as the joint between 130

it and said valve wears away and means associated therewith to prevent the escape of gases through said split portion.

4. In an engine containing a driving mechanism, a rotary valve adapted to be rotated by said mechanism, alternately presenting inlet and exhaust ports to coöperate with said mechanism, a shoe embracing said rotary valve substantially more than 180° and thus provided with means to cause it to cling to said valve, said shoe provided with portions surrounding the passageway adapted to register with the ports of said valve, said shoe having a circular projection provided with means to form a gas tight joint with a casing connected with said mechanism, said shoe surrounding said valve being split to form resilient arms to enable it to cling to said valve as the joint between it and said valve wears away and means associated therewith to prevent the escape of gases through said split portion, said means to prevent the escape of gases including an outer shoe embracing the aforementioned shoe substantially more than 180° and covering the said split portion therein.

5. In an engine containing a driving mechanism, a rotary valve adapted to be rotated by said mechanism, alternately presenting inlet and exhaust ports to coöperate with said mechanism, a shoe embracing said rotary valve substantially more than 180° and thus provided with means to cause it to cling to said valve, said shoe provided with portions surrounding the passageway adapted to register with the ports of said valve, said shoe having a circular projection provided with means to form a gas tight joint with a casing connected with said mechanism, said shoe surrounding said valve being split to form resilient arms to enable it to cling to said valve as the joint between it and said valve wears away and means associated therewith to prevent the escape of gases through said split portion, the first mentioned shoe being thinner near the split portion and the said outer shoe thicker near the said split portion, both shoes having the circular inside surfaces eccentric with the circular outside surfaces.

6. In an engine containing a plurality of cylinders, each having an inlet and exhaust passage, a driving mechanism coöoperating therewith, a single rotary valve engaged by

said mechanism to rotate it, having inlet and 55 exhaust ports adapted to register alternately with the inlet and exhaust passages in said cylinders, a plurality of shoes each embracing said rotatable valve substantially more than 180° and thus provided with means to 60 cause it to cling to said valve, said shoe provided with portions surrounding said passageways adapted to register with the ports and valve, said shoes each having a circular projection provided with means to form a 65 gas-tight joint with the corresponding cylinder of said engine.

7. The combination claimed in claim 1 having a worm gear driving device geared to said rotary valve. 70

8. The combination claimed in claim 1, having a casing formed in two parts adapted to be secured together to contain said rotary valve.

9. The combination claimed in claim 3, 75 having a casing formed in two parts adapted to be secured together to contain said rotary valve.

10. The combination claimed in claim 4, having a casing formed in two parts adapted to be secured together to contain said rotary valve. 80

11. The combination claimed in claim 5, having a casing formed in two parts adapted to be secured together to contain said rotary valve. 85

12. The combination claimed in claim 1, having two concentric gas passageways for said rotary valve, one for in-coming gases and one for out-going gases. 90

13. The combination claimed in claim 3, having two concentric gas passageways for said rotary valve, one for in-coming gases and one for out-going gases. 95

14. The combination claimed in claim 4, having two concentric gas passageways for said rotary valve, one for in-coming gases and one for out-going gases. 95

15. The combination claimed in claim 5, having two concentric gas passageways for 100 said rotary valve, one for in-coming gases and one for out-going gases.

Signed at New York, in the county of New York and State of New York, this 7th day of May, A. D. 1917.

JAMES E. DAVENPORT.
